HYDRAULIC PRESS

James L. Lefler, North Hollywood, Calif., ass'gn.
or to Bendix Aviation Corporation, South Bend,
Ind., a corporation of Delaware

Application July 12, 1945, Serial No. 604,629

1 Claim. (Cl. 60—51)

1

This invention relates to hydraulic presses and is particularly useful in hand-operated presses.

An object of the invention is to provide an inexpensive, economical press for use in operations requiring the development of large forces applied through relatively short distances.

Another object is to provide a press that utilizes an ordinary source of compressed air for effecting large movements of the press where small forces are involved, while utilizing high pressure hydraulic fluid for the development of large forces acting through only short distances.

Ordinary hydraulic presses require a power pump of substantial capacity for moving the press at a reasonable speed while at the same time developing the desired high forces. Because of the expense of power-pumping equipment, the use of hydraulic presses had been limited to situations where there was a substantial amount of press work to be done. For many purposes, it is only necessary to develop high fluid pressures in a hydraulic press during final movement of the press, and a fluid pressure as large as may be required can be developed with a relatively small and economical hand pump by making the pump piston relatively small. However, when the pump piston is made small to develop the desired high pressure, its volumetric capacity is correspondingly reduced so that it may require a great deal of time to move the press platen into position where it bears against the work-piece.

In accordance with the present invention, I provide a press that is capable of developing high forces and, at the same time, is capable of rapid movement up to the point where the high force must be generated, by providing a small capacity high pressure hand pump, in combination with means utilizing an ordinary source of compressed air for moving the press rapidly so long as only low forces are involved. The arrangement is such that only a single ram is employed on the press and only hydraulic fluid is introduced into the working chamber of the press ram, the fluid being circulated to and from the ram by air pressure during rapid movement of the press to engage and disengage a work-piece.

The manner in which the foregoing objects are attained, together with other more specific objects and features of the invention, will be apparent from the following detailed description of a preferred embodiment of the invention which refers to the drawing.

The single figure of the drawing is a schematic diagram of a system in accordance with the invention.

2

There is shown in the diagram a conventional press 1 consisting of frame vertical members 2 supporting a table 3 on which a work-piece may be placed, and supporting above the table 3 a hydraulic ram cylinder 4 containing a piston 5 having a stem 6 which extends through the bottom of the cylinder and can be moved toward the table 3 to bear against a work-piece thereon.

The upper end of the cylinder 4 above the piston 5 is connected to a fluid line 7, and the lower end of the cylinder below the piston 5 is connected to an air line 8. The upper end of the piston is at all times filled with hydraulic fluid, hereinafter referred to as oil.

15 The oil line 7 connects to a control valve 11 and also to the discharge port 12 of a hand pump 13. This hand pump comprises a relatively small diameter working cylinder 14 containing a piston 15 adapted to be reciprocated by a handle 16. The cylinder 14 is connected to the discharge port 12 past a check valve 16 and to an inlet port 18 past a check valve 17, the latter port being connected by a line 20 to the upper end of a cylinder 21 and to the valve 11. The lower end of cylinder 21 is connected by an air line 22 to the valve 11. Any ordinary source of compressed air 23 is connected by a line 24 to the valve 11.

The cylinder 21 contains a floating piston 25 which serves to maintain oil in the upper end of the cylinder separated from air in the lower part.

30 The system described operates as follows:

When it is desired to elevate the piston 5 of the ram, the valve 11 is rocked clockwise into the dotted line position labeled "Up." This connects the line 24 from the pressure air supply to the line 8 leading to the lower end of the ram cylinder so that pressure of the compressed air is applied to raise the ram piston. At the same time, oil in the upper end of the ram cylinder flows out through the line 7 and through the valve 11 to the line 20 and into the upper end of the displacement cylinder 21. This moves the piston 25 downwardly, and the air in the lower end of cylinder 21 is exhausted to atmosphere through line 22, valve 11 and an exhaust port 27 in the valve.

When it is desired to lower the piston 5 of the ram, the control valve 11 is rocked counter-clockwise into the dotted line position marked "Down." In this position, it admits pressure air from line 24 through line 22 to the lower end of the displacement cylinder 21, forcing the piston 25 upwardly to displace oil from the upper end of the cylinder through the line 20, and a check valve 28 and the line 7 into the upper end of the

ram cylinder. At the same time, the lower end of the ram cylinder is connected through line 8 and valve 11 to the exhaust port 27, so that air pressure forces oil into the upper end of the ram cylinder to move the piston 5 down. Since the air supply usually has a relatively low pressure, less than 100 p. s. i., no great force is developed by the ram after the piston rod 6 has contacted a work-piece positioned in the press. However, the operator can thereafter build up the pressure in the upper end of the ram cylinder to any desired value by reciprocating the handle 16 of the hand pump. On each outward stroke of the piston 15, it draws in oil from the upper end of cylinder 21 through the pipe 20 past the inlet check valve 17, and on each inward stroke forces such oil past the outlet check valve 16 and directly through the line 7 into the upper end of the ram cylinder.

The operator can leave the valve 11 in the "Down" position or return it to "Neutral" position, and the hand pump will be equally effective.

After the pressing operation has been completed, the operator can again raise the ram piston and piston rod to disengage the work-piece by moving the control valve 11 into the "Up" position.

Although a freely floating piston 25 has been shown in the displacement cylinder 12, its presence may not be necessary in all instances. If the piston 25 is eliminated, the oil and air connections should be reversed, i. e., the oil line 20 should be connected to the bottom of cylinder 21, and the air line 22 should be connected to the top of the cylinder. It is usually desirable to provide a barrier between the air and the oil within the displacement cylinder to prevent mixing of the air in the oil under pressure. It is common practice in accumulators for hydraulic systems to employ either a solid piston or a flexible diaphragm or a flexible bladder to prevent mixing of the oil and the air, and a flexible diaphragm or bladder may be employed in place of the floating piston 25 if desired. In such instances, it is not necessary that the displacement reservoir be in a form of a cylinder, and it may conveniently be in the form of a sphere, similar to conventional hydraulic accumulators.

Although for the purpose of explaining the invention, a specific embodiment has been described, various departures other than those men-

tioned can be made while still utilizing the invention, which is to be limited only to the extent set forth in the appended claim.

I claim:

A hydraulic press comprising: a ram cylinder containing a piston adapted to be reciprocated in one direction to press a work-piece, and in the opposite direction to release the work-piece, said ram cylinder having a liquid opening in one end for receiving liquid to move the piston in said one direction, and an air opening in the other end, a source of compressed air under medium pressure, a closed reservoir for hydraulic liquid and air and having a liquid opening and an air opening, a high-pressure, low volumetric capacity pump having an inlet opening and an outlet opening, said pump being adapted to develop pressures much greater than the pressure of said air source, check valve means interconnecting said liquid openings of said ram cylinder and reservoir for permitting flow from said reservoir to the ram cylinder, while preventing reverse flow, a control valve having first, second, and third positions and connections extending from said ram cylinder, said air source, said reservoir, and said pump to said valve; said valve when in said first position connecting the liquid opening of said reservoir to the liquid opening of said ram, connecting said air source to the air opening of the ram cylinder, and connecting the air opening of said reservoir to atmosphere, whereby said ram piston is moved in said other direction and liquid in the ram cylinder is returned to said reservoir; said valve when in said second position connecting said air source to the air opening of said reservoir, and connecting the air opening of said ram cylinder to exhaust, whereby liquid is displaced from said reservoir, through said check valve means into the ram cylinder to move the ram piston in said one direction with low force; said valve, when in said third position, connecting the air openings of said ram cylinder and reservoir to exhaust; and means connecting the liquid opening of the ram cylinder to the outlet of the pump, and connecting the liquid opening of the reservoir to the inlet of the pump, whereby actuation of the pump forces liquid into said liquid opening of the ram cylinder to develop high force on the piston there-

in.
